WALL MOUNTED JEWELRY HOLDER

John H. Reger, 2558 W. Illinois Blvd., Dallas, Tex.

Filed May 21, 1962, Ser. No. 70,226

Term of patent 14 years

(Cl. D33—3)

FIG. 1

FIG. 2

FIG. 3

I claim:

The ornamental design for a wall mounted jewelry holder, substantially as shown and described.
